UNITED STATES PATENT OFFICE.

GEORGE B. WALKER, OF WASHINGTON, DISTRICT OF COLUMBIA, ASSIGNOR, BY MESNE ASSIGNMENTS, TO A-B-C TRANSIT REFRIGERATION COMPANY, OF NEW YORK, N. Y., A CORPORATION OF DELAWARE.

REFRIGERATING APPARATUS.

Application filed January 14, 1921. Serial No. 437,333.

To all whom it may concern:

Be it known that I, GEORGE B. WALKER, a citizen of the United States, residing at Washington, District of Columbia, have invented certain new and useful Improvements in Refrigerating Apparatus, of which the following is a specification.

This invention relates generally to refrigerating apparatus, and particularly to a portable refrigerating device designed particularly for use in stores or the like or on trucks wherein commodities, such for example, as ice cream, are retailed, or in transit.

My improved refrigerating apparatus is more particularly intended for the reception of the usual ice cream can, and is designed to maintain the contents of the can under a substantially uniform, low temperature, while permitting free access to the interior of the can to dispense the contents thereof as may be required.

The invention is constructed to provide a refrigerating chamber in which a liquid, such as water is subjected to the cooling influence of ice and salt to produce a refrigerating brine, and such brine caused to circulate through coils arranged in the storage compartment with said coils arranged to form an envelope to receive the usual ice cream can. The can receiving openings in the storage compartment are provided with means for cooperation with the ice cream cans to effectively seal the compartment against the escape of the air therein when the covers of the compartment are removed to provide access to the interior of the cans. The gradual cooling of the air in this compartment, due to the refrigerating coils, reduces the volume thereof to an extent to produce a partial vacuum therein, which will act as a non-conductor against the passage of the outside heated condition to the coils.

An essential feature of the present invention is a means whereby the circulation of the refrigerating agent is obtained. The invention takes advantage of the natural law of a liquid seeking its level and in providing means to continuously and at successive intervals lift a quantity of the refrigerating agent from one side of the circulating path and transferring it to the other, so varies the level of the refrigerating agent

as to cause a circulation in a restoration of such level.

In the drawings:

Figure 1 is a perspective view of the improved refrigerating apparatus.

Figure 2 is a central longitudinal section of the apparatus.

Figure 3 is a transverse section on the line 3—3 of Figure 5.

Figure 4 is a detail perspective view of the brine lifting element.

Figure 5 is a top plan view of the apparatus, with a part of the top, and a part of the casing removed.

In the form illustrated the refrigerating apparatus is shown to provide what may be termed an ice cream cabinet, designed particularly for the convenient reception of a number of ice cream cans, and for use in stores or the like where ice cream is to be dispensed and retailed. Ordinarily the storage of ice cream under these conditions is, by means of an ice box in which the cans are placed, the spaces about the cans being periodically packed with ice. This manner of maintaining the ice cream in saleable condition requires the ice cream manufacturer or distributor to periodically visit the stores he is serving, and pack or re-pack the refrigerators with ice and salt. This manner of maintaining the ice cream in saleable condition requires a large quantity of ice, the transporation of the same to the various stores, and a considerable amount of labor, time and expense on the part of the distributor. It is to a view of avoiding this material expense, ice transportation, and labor, to a more or less considerable degree that the present refrigerating apparatus is designed.

As constructed the improved ice cream cabinet comprises what may be termed a refrigerating compartment 1, of box-like form and of appropriate size, divided by a longitudinal partition 2, extending throughout the height of the compartment and the full length thereof, providing what may be termed a brine chamber 3. Between the partition 2 and the opposite side wall of the chamber there is arranged adjacent one end wall a vertical partition 4 providing with said end wall a receiving chamber 5. A similar partition 6 is arranged adjacent the opposite end wall of the compartment, said

partition 6 extending from the partition 2 to the opposite side wall of the compartment, forming with the adjacent end wall a delivery chamber 7. The relatively opposite ends of the partitions 4 and 6, that is, the lower end of the partition 4 and the upper end of the partition 6, are appropriately perforated at 8, these perforated or foraminous sections of the respective partitions being of the full width of the partition and of appreciable height for the purpose designed.

The space included between the partition 2 and the side wall of the compartment and the partitions 4 and 6, provides an ice storage chamber 9 into which ice and salt in the appropriate proportions are to be initially placed. This ice storage chamber has a convex bottom 10, providing between the same and the bottom 11 of the compartment an excess storage chamber 12, preferably having a manually control drain 13. An overflow pipe 14 leads to the chamber 12 from the receiving chamber 5, this overflow pipe having a trap formation 15 near the upper end, and having its upper end 16 open to the interior of the receiving chamber at the height determined for the proper water level.

The brine lift in this instance comprises a trough-like member 17 pivotally supported at 18 in the chamber 3 and adjacent the receiving chamber 5. That end of the trough member 17 next the receiving chamber is opened, as at 19, and is adapted to deliver the brine into a trough 20, which leads into the receiving chamber near the upper end thereof. The end of the trough remote from the open end has an inclined end wall 21, to permit the more convenient entrance of the brine, and the trough is operated on its pivotal support through a link 22 connected to such trough and reciprocated by a motor 23, of any usual or preferred type supported upon the closed top of the compartment, and operated in any way.

In connection with the refrigerating compartment, the present structure contemplates the provision of a storage compartment 24, connected to or forming a part of a refrigerating compartment. The storage compartment is adapted to receive a series of coils 25, arranged to present an interior space of a size to more or less accurately receive an ice cream can as 26. The coils are thus arranged closed about the exterior of the can to provide the most beneficial effect of the refrigerating medium. The coils, of which there may be any number, in accordance with the contemplated capacity of the structure, are connected in series, the initial coil having an inlet pipe 27 leading from the delivery chamber 7 of the refrigerating compartment, while the final coil has an outlet or delivery pipe 28 leading

into the lower end of the brine chamber 3. The inlet pipe 27 leads from the delivery chamber 7 near the upper end of the latter, so that there is a gravitational influence in the travel of the refrigerating agent through the coils.

The storage compartment, otherwise sealed, is formed with openings 29 in line with the can receiving spaces formed by the coils, which openings are adapted to be properly closed when desired by cover sections 30 to seal the openings. In this connection it is important that the interior of the storage compartment beyond the surface of the ice cream cans be more or less sealed at all times, and as it is necessary to remove the covers 30 to gain access to the interior of the ice cream cans, some additional sealing means must be provided. For this purpose, the present invention contemplates a gasket 31, preferably of rubber, secured to the interior of the top of the storage compartment adjacent each can opening therein. These gaskets are formed with central openings 32 to permit the passage of a can therethru, in introducing or removing the can, these openings 32 being slightly less in diameter than the exterior diameter of the can. The edge of the can opening 32 of these gaskets yield as the can is introduced, and as the can reaches a resting place, such edges are designed to ride past the usual rib 33 formed on said cans and closely grip the surface of the can above such rib. This completely seals the interior of the storage compartment beyond the can, notwithstanding the fact that the cover 30 may be removed to reach the ice cream.

The interior of the storage compartment beyond the coils is designed to have a cork or other filling 34, and it is contemplated that in the initial use of the refrigerating apparatus, the air in the storage compartment beyond the coils will, through the refrigerating effect of the coils, be so reduced in temperature as to materially reduce its volume and thus in a measure form what may be said to be a partial vacuum protection for the cans against heat influences from beyond the storage compartment.

With the refrigerating apparatus constructed and arranged as described, it will be apparent that with ice and salt in the chamber 9 of the refrigerating compartment, and an appropriate amount of water in the brine chamber 3, the trough 17 will in its movement resulting from the operation of its motor, pick up the brine from the chamber 3 and deliver it by gravity to the receiving compartment 5. The brine can only flow from this compartment through the foraminous portion 8 of the partition 4, travelling thence to and mixing through the ice and salt, being thereby converted into a cooling medium, and rising thru the foraminous

portion 8 of the partition 6 into the delivery compartment 7. The brine then flows by gravity thru the inlet pipe 7 to and thru the successive coils, returning thru the delivery pipe 28 to the chamber 3. A substantially continuous circulation of the brine is thus maintained as long as the motor is operated, and the contents of the ice cream can are kept at a low temperature. In this connection it has been demonstrated that the water absorbs substantially 22% of the salt, and if maintained in substantially continuous circulation, will produce a temperature averaging approximately zero or slightly less than zero.

The excess brine naturally accumulating thru the melting of the ice is taken care of by the overflow pipe 14 and may be discharged from the apparatus as found necessary. Owing to the constantly low temperature maintained, it will be found that the apparatus when once in operation requires practically no attention except a periodical renewal of the ice and salt, and this renewal is at very infrequent intervals, as compared with the present ice charging of the ice cream cabinets. Hence the manufacturer or distributor is saved the expense of the additional material and also the time and labor of transporting the same and packing the cabinets.

It is of course to be understood that the invention as herein described, is designed more particularly as an ice cream cabinet for the storage of ice cream in cans so that it may be readily dispensed in retail stores without material change in condition, and that it is adapted to receive any desired number of cans. It is also to be understood that the improvement is in no wise limited in use to ice cream, and it is evident it may be employed in any art where refrigeration is necessary.

It is to be noted that the brine lift is in no sense a pump, and that its acts merely to lift a quantity of the brine from the chamber 2, which constitutes the final chamber on one side of the circulating system to the receiving chamber 5, which constitutes the initial chamber on the other side of the circulating system. The level of liquid between the chambers 2 and 5 is thus periodically and continuously changed in favor of the chamber 5, so that in the attempt of the brine to seek its level, a circulation is maintained. In connection with this circulation, it will be apparent that with a comparatively slow uniform action of the lift, the brine is not in constant circulatory movement, as when the liquids in the respective chambers gradually approach and finally reach a level, the circulation is gradually retarded and finally brought momentarily to rest until the levels in the chambers 2 and 5 are again changed in the action of the lift.

This permits a most effective refrigerating action in the coils, as the moving refrigerant has ample time to absorb the heat from the contents of the cans.

Claims:—

1. A refrigerating apparatus comprising a refrigerating compartment, having a brine lifting chamber at one side, a receiving chamber at one end, a delivery chamber at the opposite end, and an ice chamber between the receiving and delivery chambers, the receiving chamber communicating with the ice chamber at the lower portion of the latter and the delivery chamber communicating with the ice chamber at the upper portion of the latter, a brine lifting element pivoted in the brine chamber, means for moving the brine lifting element up and down in the brine chamber to pick up the brine therefrom, and means for delivering the brine from the brine lifting element to the receiving chamber.

2. A refrigerating apparatus comprising a refrigerating compartment, having a brine chamber at one side, a receiving chamber at one end, a delivery chamber at the opposite end, an ice chamber between the receiving and delivery chambers, a brine lifting element pivoted in the brine chamber, means for moving the brine lifting element up and down in the brine chamber to pick up the brine therefrom, and means for delivering the brine from the brine lifting element to the receiving chamber, the receiving chamber and ice chamber having communication at the lower ends of said chambers and the delivery chamber and ice chamber having communication at the upper end of said chambers.

3. A refrigerating apparatus comprising a refrigerating compartment including a box-like member having a partition extending lengthwise the same adjacent one side to provide a brine chamber, a pivoted brine lifting element operating in said chamber, transverse partitions extending from the first-mentioned partition to the opposite side wall of the receptacle and adjacent each end of the receptacle to provide receiving and delivering chambers, means to deliver the brine from said brine lifting element to the receiving chamber, the partition defining the receiving chamber being perforated near its lower end, the partition defining the delivery chamber being perforated near its upper end, the space between the partitions and side wall of the receptacle defining an ice chamber.

4. A refrigerating apparatus for ice cream cans comprising a storage compartment including a series of coils defining can receiving spaces, means arranged beyond said coils to force the circulation of a refrigerating medium thru the coils, the top of the storage compartment having openings

in line with the can receiving spaces, closures sealing said openings, and a flexible sealing gasket secured at the top of each opening of the storage compartment below said closures and having an opening of slightly less diameter than that of the can to seal the interior of the compartment about the can when the latter is inserted.

5. A refrigerating apparatus for ice cream cans comprising a storage compartment including a series of coils defining can receiving spaces, means arranged beyond said coils to force the circulation of a refrigerating medium thru the coils, the top 10 of the storage compartment having openings in line with the can receiving spaces, closures sealing said openings, and an annular flexible sealing gasket secured to the underside of each closure and having an 15 opening of slightly less diameter than that of the can to seal the interior of the com- 20

partment about the can when the latter is inserted, and a cork filling for the interior of the compartment beyond the coils.

6. A refrigerating cabinet, comprising an 25 outer receptacle, a circulating conduit housed therein and located an appreciable distance from the side walls thereof, said conduit being in the nature of a hollow jacket shaped to receive and closely encompass a container, insulating material in the space between the receptacle and said circulating conduit, a tank in the casing adapted for the retention of ice, said conduit 30 communicating at its terminals with the tank, and means for inducing a flow of the refrigerant through said cooling tank and the conduit.

40 In testimony whereof I affix my signature.

GEORGE B. WALKER.
